UNITED STATES PATENT OFFICE.

ROLLIN F. WEBBER, OF WASHINGTON, DISTRICT OF COLUMBIA.

STARTING DEVICE FOR EXPLOSIVE-ENGINES.

1,160,476.

Specification of Letters Patent.

Patented Nov. 16, 1915.

Application filed July 3, 1911. Serial No. 636,794.

To all whom it may concern:

Be it known that I, ROLLIN F. WEBBER, citizen of the United States, residing at Washington, District of Columbia, have invented certain new and useful Improvements in Starting Devices for Explosive-Engines, of which the following is a specification, reference being had therein to the accompanying drawing.

10 This invention relates to an improvement in starting devices for explosive engines and more particularly to an improvement in starting devices of the general type disclosed in the application of Rollin F. Webber and 15 George W. Slater, filed March 19, 1910, Serial No. 550,518.

In this type of starter, the starting of the motor is effected by the shifting of an actuating arm or member which is operatively 20 associated with the motor shaft and between which and the motor shaft is interposed a pawl and ratchet connection, and means are provided for automatically throwing the 25 pawl to a position to engage the ratchet wheel of the engine shaft upon movement of the actuating arm or member in one direction and for automatically disengaging the pawl from its ratchet upon movement of the actuating arm or member in the opposite 30 direction and upon a reverse movement of the motor shaft.

The object of the present invention is the provision in a starting device of this character of improved means for actuating the 35 pawl to throw the same into and out of operative position.

A further object of the present invention is the provision in a starting device of this character, of means for throwing the pawl into engagement with the ratchet wheel, of 40 such a construction that after the actuating arm or member has been moved a sufficient distance to cause the pawl actuating means to throw the pawl into engagement with the 45 ratchet wheel, said pawl actuating means will maintain its operative connection with the pawl during the remainder of the movement of the actuating arm or member, so that at any time during such remainder of 50 the stroke the pawl will, when the actuating member is moved in one direction, be caused to automatically engage the ratchet and when the actuating member is moved in the other direction, the pawl will be automatically 55 disengaged from the ratchet. This is

an important feature of the invention as it enables the operator to spin the engine shaft by imparting to the actuating member a series of reciprocations after the same has been moved beyond the point where the pawl 60 actuating means has been shifted into operative connection with the pawl.

A further object of the invention is the provision in a starting device of this character of improved means for varying the time 65 at which the pawl will be thrown into operative position.

Other objects of the invention will be apparent from the detailed description hereinafter when read in connection with the accompanying drawings forming a part hereof, wherein a convenient embodiment of the invention is illustrated, and wherein like characters of reference refer to similar parts in the several views.

In the drawings:—Figure 1 is a front elevation of the improved starting mechanism showing parts in their inactive position. Fig. 1^a is an enlarged view of a portion of the mechanism illustrated in Fig. 1. 80 Fig. 2 is a side elevation of the mechanism illustrated in Fig. 1, parts being broken away. Fig. 3 is a front elevation of the mechanism illustrated in Fig. 1, the pawl of the actuating arm having been thrown into 85 engagement with the ratchet wheel on the engine shaft. Fig. 4 is a longitudinal section through the actuating arm of the device, and Fig. 5 is a detailed view illustrating the manner of connecting the operating 90 lever and link which extends therefrom to the actuating arm.

Referring now more particularly to the drawings, A indicates an explosive engine which is adapted to be suitably mounted in a 95 vehicle frame of the usual construction and A' the shaft of such engine. Keyed upon the shaft A' of the engine A is a ratchet wheel A².

Journalized in a suitable bearing carried 100 by the frame of the vehicle and in alignment with the engine shaft A', is a stub shaft B and rigidly mounted upon said stub shaft is an actuating arm C to the inner face of which is pivoted a ratchet or dog c which 105 is adapted to coöperate with the ratchet wheel A² upon the engine shaft. The dog or ratchet c is in the form of a bell crank lever, the short arm of which constitutes the nose of the pawl which is adapted to engage the 110

teeth of the ratchet wheel A² and the long arm of which extends alongside of the inner surface of the actuating arm C.

Projecting laterally from the long arm of the pawl or dog c adjacent the pivot point of the pawl, is a pin or stud c' for a purpose to be hereinafter more particularly set forth.

Positioned at one side of the stub shaft B, hereinbefore referred to, and pivotally supported at its lower end, in any suitable manner from the frame of the vehicle, is an upstanding lever D. The lever D is of greater length than the length of the actuating arm C and the length of said lever also preferably exceeds the distance between its pivot and the pivot of the actuating arm C, so that such lever may be moved to a position with the free end thereof overlying the engine shaft, as shown in Fig. 1. In this connection it will be understood that while it is stated that the lever D is pivotally supported at one side of the shaft B so that the free end of such lever may be moved to a position to overlie said shaft, the lever may be positioned at any point around the shaft B and the parts operatively connected thereto will be positioned accordingly. The free end of the lever D is pivotally connected to the free end of the actuating arm C by means of an elongated downwardly curved link E, which link is of greater length than the distance between the pivot pin of the arm C and lever D. The link E is pivotally connected to the side of the actuating arm C upon which is supported the dog c and such link is provided at its other end with a bifurcated portion between which the outer end of the lever D is pivotally supported, said bifurcated portion being so disposed that the lever D and the link E will be positioned in substantially the same vertical plane. The lever D has secured to its lower end a segment D' which is provided with a curved periphery for the reception of an actuated cable F, which is seated in the grooved periphery of the segment and has one end thereof anchored to one end of said segment in any suitable manner. The cable F extends from the segment D' around a horizontally disposed idler G which is adapted to be supported in any suitable manner from the frame of the vehicle, and from thence rearwardly of the frame of the vehicle. The opposite end of the cable is adapted to be operatively connected in any suitable manner to operating mechanism whereby a pull may be exerted on the cable at the will of the operator. Any suitable form of operating device or handle may be used for this purpose and I have deemed it unnecessary to illustrate any particular construction for accomplishing this result in the present application.

The link E is connected to the actuating arm C by means of a pivot bolt H, which

comprises a cylindrical body portion h which is adapted to loosely engage aligned apertures in the actuating arm C and the end of the link E, and which terminates in a reduced portion h' which projects beyond the actuating arm C and upon which is adapted to be threaded a securing nut h² for holding the bolt in position. The opposite end of the body portion h of the bolt terminates in an enlarged circular portion h³ which is adapted to lie upon the outer surface of the link E and a head h⁴ which is of greater diameter than the circular portion h³. In practice the head h⁴ of the bolt H is made in circular form and a portion of the periphery thereof is cut away as at h⁵. Extending through the link E and engaging the portion of the bolt H which passes therethrough is a set screw h⁶, which serves to rigidly lock the bolt to the link, but which permits said bolt to be adjusted circumferentially in said link. Loosely mounted on the circular portion h³ of the bolt between the head h⁴ thereof and the link E is an arm I which is adapted to overlie the long arm of the pawl or dog c and which is provided in the outer end thereof with a longitudinally disposed slot i which loosely engages the stud c' projecting from the long arm of said pawl or dog. Secured to the exterior of the arm I is a plate K, which is conveniently formed of spring metal, and which is provided with a segmental flange k projecting laterally from one end thereof and underlying the periphery of the bolt. The spring plate K is provided with a slot k' extending longitudinally thereof and is adjustably secured to the arm I by means of screws passing through said arm, so that the plate may be adjusted to bring the flange k thereof toward or away from the periphery of the head h⁴ of the bolt H. In practice the plate K is so adjusted that the flange k thereof will normally contact with the main portion of the periphery of the head h⁴ of the bolt but will not contact with the cut away portion h⁵ thereof.

The normal position of the parts is indicated in Fig. 1 and all of the parts of the device are normally maintained in this position by a suitable spring L which is preferably interposed between the actuating arm C and the frame of the machine. It will be noted that when the parts are in this position, the pawl is out of engagement with its ratchet and the flange k of the plate K is positioned within the cut away portion of the periphery of the head h⁴ of the bolt H. With the parts in this position, to start the engine the operator pulls upon the cable F, thus rocking the lever D on its pivot and turning the actuating arm C around its pivotal support, through the link connection between said lever and actuating arm. During this movement of the parts, the angle be-

tween the link E and the actuating arm will be gradually increased, and as the bolt H is rigid with the link E, and is loose in the actuating arm C, it will be turned relatively 5 to said arm and the circular portion of the periphery of the head h^4 of said bolt will be moved into frictional engagement with the segmental flange k of the spring plate K, and as the parts continue to move, the arm 10 I will by reason of such frictional engagement between the head of the bolt and the flange k of the plate K, be caused to swing on the bolt, which will, through the pin and slot connection between the arm I and the 15 long arm of the pawl or dog c , throw said pawl or dog into engagement with the teeth of the ratchet wheel A² on the engine shaft. By reason of the employment of the relatively long pawl actuating member I, and by 20 reason of the fact that such arm is connected to the pawl adjacent its pivot point, it will be seen that the movement of the pawl will be much more rapid than that of the actuating arm C so that the pawl will be thrown 25 into engagement with its ratchet almost immediately after the engagement of the circular portion on the head h^4 of the bolt H with the segmental flange k of the spring plate K. As soon as the pawl is thrown into 30 engagement with the teeth of the ratchet wheel, such pawl will be held against further movement on its pivot and during the remainder of the movement of the parts, the curved portion of the head h^4 of the bolt will 35 slip over the segmental flange k of the spring plate K. As soon as the engine has been started, and the pull on the cable F is released, the spring heretofore referred to will restore the parts to normal position. During 40 the return movement of the parts, the bolt head h^4 will, of course, be shifted relatively to the actuating arm C, and as the resistance on the nose of the pawl has been relieved, such movement of the bolt head 45 will, through its engagement with the segmental shaped flange k on the plate K, shift the arm I and lift the pawl out of engagement with the ratchet wheel. Should the engine shaft turn in a reverse direction, or 50 "kick back," the pawl, if in engagement with its ratchet wheel, would remain in this position, by reason of the frictional engagement between the teeth of said ratchet wheel and the nose of the pawl, and the head would 55 ride over the flange k of the plate E without effecting the disengagement of the pawl from its ratchet, and I therefore prefer to provide some positive means for ejecting the pawl in the event of this occurrence. In the 60 construction shown in the drawings, such means comprises a projection E' which extends downwardly from the link E adjacent its connection with the actuating arm, and is so positioned that as the parts are returned 65 to normal position, it will engage the long

arm of the dog or pawl c and force the same out of engagement with the ratchet, as is clearly shown in Fig. 1. As the projection E' which extends from the link E engages the arm of the actuating pawl and shifts 70 such pawl, the nose of the pawl will be caused to contact with the lower edge of the link E, thus constituting a stop to limit the movement of said link, as is clearly shown in Fig. 1^a. If desired, a buffer may be inter- 75 posed between the nose of the pawl and the link and in the drawings I have shown the link provided with such a buffer e of rubber or other suitable material, at the point where such link engages the nose of the pawl. 80

It will be noted that after the parts have been so shifted to bring the circular portion h^4 of the bolt H into engagement with the segmental flange k of the plate K, such circular portion will remain in engagement 85 with said flange during the remainder of the movement of the actuating arm. This is an important feature of the present construction as it enables the actuating member to be reversed a slight distance and then again 90 moved forward when the pawl will be thrown into engagement with the ratchet wheel, whereas in the structure of the type shown in the Webber and Slater application, heretofore referred to, it was necessary to 95 return the actuating arm to its initial position at all times before the pawl could be engaged with the ratchet wheel. The present construction enables the operator to spin the engine shaft by imparting a series of 100 short reciprocations to the actuating arm C, after such arm has once been moved far enough to bring the pawl actuating member into operative connection with the pawl.

It will also be noted that with the present 105 construction, by adjusting the bolt H in the link E, the time of actuating the pawl may be regulated so that such pawl will be thrown into engagement with its ratchet after any desired amount of movement of 110 the actuating arm C.

I do not desire to claim broadly in the present application, a starting device for 115 motors including a pawl and ratchet coupling between the actuating parts of the device and the motor shaft, means for automatically throwing the pawl into engagement with its ratchet, and means for adjusting said last mentioned means to vary the time of actuation of said pawl, as I 120 have claimed such invention broadly in my co-pending application, filed July 3, 1911, Serial No. 636,793.

While I have illustrated a convenient 125 embodiment of the invention in the accompanying drawings, it will be noted that many changes may be made to the form and construction therein shown without departing from the spirit and scope of the invention as defined in the appended claims. 130

What I claim is:—

1. A starting device for motors including a pawl and ratchet connection operatively associated with the engine shaft, an actuating member carrying said pawl, operating means for the actuating arm, pawl throwing means adapted upon movement of said actuating member by said operating means in one direction to throw the pawl into engagement with the ratchet and adapted during movement of the actuating member by the operating means in the opposite direction to disengage the pawl from the ratchet, and means for operatively connecting said pawl throwing means with said pawl after a predetermined amount of movement of the actuating member and maintaining said operative connection throughout the remainder of movement of the actuating member.

2. The combination with a motor, of means for starting the same including a pawl and ratchet connection operatively associated with the engine shaft, an actuating member carrying said pawl and movable about said shaft, means acting automatically after a predetermined amount of movement of the actuating member to throw the pawl into engagement with the ratchet, said means including frictionally engaging members adapted to slip one upon the other after the pawl has been thrown into engagement with its ratchet.

3. The combination with a motor, of means for starting the same including a pawl and ratchet connection operatively associated with the engine shaft, an actuating member carrying said pawl and movable about said shaft, means acting automatically after a predetermined amount of movement of the actuating member to throw the pawl into engagement with the ratchet, said means including frictionally engaging members adapted to slip one upon the other after the pawl has been thrown into engagement with its ratchet, and means for varying the time of throwing the pawl into engagement with its ratchet.

4. The combination with a motor, of means for starting the same including a pawl and ratchet connection operatively associated with the engine shaft, an actuating arm carrying said pawl and movable about said shaft, means for shifting said actuating arm including a movable part connected thereto, and means interposed between said movable part and the pawl for throwing the pawl into engagement with its ratchet upon shifting the actuating arm, said means including frictionally engaging members adapted to slip one upon the other after the pawl has been thrown into engagement with its ratchet.

5. The combination with a motor, of means for starting the same including a

pawl and ratchet connection operatively associated with the engine shaft, an actuating arm carrying said pawl and movable about said shaft, means for shifting said actuating arm including a movable part connected thereto, and means interposed between said movable part and the pawl for throwing the pawl into engagement with its ratchet upon shifting the actuating arm, said means including frictionally engaging members adapted to slip one upon the other after the pawl has been thrown into engagement with its ratchet, and means on said movable part for engaging the pawl and positively holding the same out of engagement with the ratchet in the reverse movement of the device.

6. The combination with a motor, of means for starting the same including a pawl and ratchet connection operatively associated with the engine shaft, an actuating member carrying said pawl, means for shifting said actuating member including a part movable therewith, and an arm shiftable with said movable part, and a loose connection between the free end of said arm and said pawl adjacent the pivot point thereof.

7. The combination with a motor, of means for starting the same including a pawl and ratchet connection operatively associated with said engine shaft, an actuating arm carrying said pawl, a pivoted pawl throwing arm movable with said actuating arm and having a loose connection directly with said pawl, and means acting automatically upon movement of said actuating arm for swinging the pawl throwing arm to shift the pawl.

8. The combination with a motor, of means for starting the same including a pawl and ratchet connection operatively associated with the engine shaft, an actuating member carrying said pawl, means for shifting said actuating member including a movable part connected thereto, a pivoted pawl actuating arm movable with said actuating member, and means carried by said movable part for shifting said pawl actuating arm to throw the pawl into and out of operative position.

9. The combination with a motor, of means for starting the same including a pawl and ratchet connection operatively associated with the engine shaft, an actuating member carrying said pawl, means for shifting said actuating member including a movable part connected thereto, a pivoted pawl actuating arm movable with said actuating member, and means carried by said movable part for shifting said pawl actuating arm to throw the pawl into and out of operative position, and means for adjusting said last mentioned means to vary the time of actuation of the pawl.

10. The combination with a motor, of

means for starting the same including a pawl and ratchet connection operatively associated with said engine shaft, an actuating arm carrying said pawl, means for operating said actuating arm including a movable part connected thereto, a pivoted pawl throwing arm movable with said actuating arm and operatively connected with said pawl, and means carried by said movable part for frictionally engaging said pawl throwing arm to shift the same after a predetermined movement of the actuating arm.

11. The combination with a motor, of means for starting the same including a pawl and ratchet connection operatively associated with the engine shaft, an actuating arm carrying said pawl, means for shifting said actuating arm including a movable part connected thereto, a pivoted pawl throwing arm movable with said actuating arm and operatively associated with said pawl, means carried by said movable part for frictionally engaging said pawl throwing arm to shift the same after a predetermined movement of the actuating arm, and means for adjusting said last mentioned means to vary the time of its engagement with the pawl throwing arm.

12. The combination with a motor, of means for starting the same including a pawl and ratchet connection operatively associated with said engine shaft, an actuating arm carrying said pawl, means for shifting said arm including a part movable therewith, a pivoted pawl throwing arm movable with said actuating arm and operatively connected to said pawl, and means for shifting said pawl throwing arm including members carried by the pawl throwing arm and the movable part, and adapted to be moved into frictional engagement with each other after a predetermined amount of movement of the actuating arm, and means for adjusting one of said members relatively to the other.

13. The combination with a motor, of means for starting the same including a pawl and ratchet connection operatively associated with the engine shaft, an actuating arm carrying said pawl, operating means for said actuating arm including a link, a pivot bolt rigid with said link and loosely engaging said actuating arm, a pawl throwing arm loosely mounted on said pivot bolt and operatively connected to said pawl, and means carried by said link for shifting said pawl throwing arm.

14. In a starting device for motors, the combination with an engine shaft, a ratchet wheel thereon, an arm movable about said engine shaft, a pawl carried by said arm, operating means for said arm including a link pivotally connected thereto, and means interposed between said link and said pawl for automatically throwing the pawl into

engagement with the ratchet after a predetermined amount of movement of the actuating arm, said means including frictionally engaging members adapted to slip one upon the other, after the pawl has been thrown into engagement with the ratchet.

15. The combination with a motor, of means for starting the same including a pawl and ratchet connection operatively associated with the engine shaft, an actuating arm carrying said pawl, means for operating said arm including a link, a pivot bolt rigid with the link and loosely engaging said actuating arm, a pawl throwing arm loosely mounted on said pivot bolt, and operatively connected to said pawl, said pawl throwing arm being provided with a portion lying in the path of the periphery of said pivot bolt and adapted to be frictionally engaged thereby upon the operation of the device.

16. The combination with a motor, of means for starting the same including a pawl and ratchet connection operatively associated with the engine shaft, an actuating arm for said pawl, means for shifting said arm including a link, a pivot bolt connecting said link and said actuating arm, a pawl throwing arm loosely mounted on said pivot bolt and operatively connected to said pawl, means for actuating said pawl throwing arm comprising a resilient member carried by the arm, said pivot bolt being movable with the link and disposed to frictionally engage said resilient member during the operation of the device.

17. The combination with a motor, of means for starting the same including a pawl and ratchet connection operatively associated with the engine shaft, an actuating arm for said pawl, means for shifting said actuating arm including a link, a pivot bolt rigid with said link and loosely engaging said actuating arm, said bolt being provided with a head having a portion of its periphery cut away, a pawl throwing arm loosely mounted on said bolt and operatively connected to said pawl, said pawl throwing arm being provided with a portion lying in the path of the periphery of said bolt and adapted to be frictionally engaged thereby.

18. The combination with a motor, of means for starting the same including a pawl and ratchet connection operatively associated with the engine shaft, an actuating arm for said pawl, means for shifting said actuating arm including a link, a pivot bolt rigid with said link and loosely engaging said actuating arm, said bolt being provided with a head having a portion of its periphery cut away, a pawl throwing arm loosely mounted on said bolt and operatively connected to said pawl, said pawl throwing arm being provided with a portion lying in the path of the periphery of said bolt and adapted to be frictionally engaged thereby,

and means for circumferentially adjusting the pivot bolt in the link.

19. A starting device for motors including a pawl and ratchet, an arm on which 5 said pawl is pivotally mounted, means connected with said arm for operating the same including a movable part pivoted to the arm, means acting automatically to throw the pawl into engagement with its ratchet upon 10 a forward movement of the arm, said movable part being provided with portions adapted to positively engage the pawl at each side of its pivot point, upon a reverse movement of the actuating arm.

15 20. In a starting device for motors, the combination with an engine shaft, a ratchet wheel thereon, an arm movable about the engine shaft, a pawl carried by said arm, means for operating said actuating arm in-

cluding a link, a pivot bolt connecting said link and said actuating arm, a pawl throwing arm loosely mounted on said pivot bolt, and operatively connected to said pawl, a plate carried by said pawl throwing arm and provided with a laterally projecting 25 resilient segmental flange, said pivot bolt being movable with the link and having a curved segmental face adapted to engage the segmental flange of the plate of the pawl throwing arm, during the actuation of the 30 device.

In testimony whereof I affix my signature in presence of two witnesses.

ROLLIN F. WEBBER.
